UNITED STATES PATENT OFFICE.

JULIUS G. BALCERWICZ, OF GRAND RAPIDS, MICHIGAN, ASSIGNOR OF ONE-HALF TO
KARL H. REYNIER, OF GRAND RAPIDS, MICHIGAN.

INTERLOCKING CHAIN LINKS.

Application filed October 28, 1922. Serial No. 597,494.

To all whom it may concern:

Be it known that I, JULIUS G. BALCERWICZ, a citizen of the United States, residing at Grand Rapids, in the county of Kent and State of Michigan, have invented new and useful Improvements in Interlocking Chain Links, of which the following is a specification.

The present invention relates to interlocking chain-links; and its object is to provide such links which may be readily interlocked or connected and readily disconnected or unlocked as may be desired, and which will, when interlocked, be securely held against accidental unlocking.

This object is attained by, and the invention finds preferable embodiment in, the chain-link structure hereinafter described and illustrated by the accompanying drawing, in which:

Figure 1 is a plan view of a chain showing my interlocking links;

Figure 2 is a side view thereof;

Figure 3 is a transverse sectional view of one of the interlocking links taken on line 3-3 of Figures 1 and 2;

Figure 4 is a side view of the interlocking links, illustrating their interrelative positions at the beginning of the operation of interlocking the same;

Figure 5 is a similar view illustrating said links in other and subsequent positions of said operation;

Figure 6 is a side view of the "first" interlocking link; and

Figure 7 is a side view of the other (the "second") interlocking link and a portion of a connected ordinary chain-link.

My first interlocking link 1 has opposite sides 2, spaced apart and connected at one end of the link by the bight portion 3, and has also a tongue 4. This tongue is carried by the middle part of the bight portion 3 and extends (as particularly shown in Figures 1 and 3) in planes which are spaced inwardly from the sides 2, so that a clearance space is provided between the tongue and the sides 2 on either side of the tongue. The tongue thus desirably extends (as particularly shown in Figures 2, 4, 5 and 6) first in the longitudinal direction of the link outwardly at 6 from the bight portion and then extends in bowed form, as seen at 7, outwardly from the sides 2, and then approaching said sides, to its point or ex-

tremity 8 which is desirably between said sides 2. The second interlocking link 9 has opposite sides 10 which are parallelly U-shaped (as particularly shown in Figures 2, 4, 5 and 7) such sides 10 being connected by bight portions 11, 12.

In the operation of interlocking the links 1 and 9, the bight portion 12 of the "second" link 9 is inserted between the sides 2 of the "first" link 1 (as seen in dotted lines at A in Figure 4), and the bight portion 11 of the second link 9 is swung (as seen in solid lines in Figure 4) between the sides 2 and hooked over or passed around the point or extremity 8 of the first link's tongue 4, and is then moved along the tongue in a turning movement (successive positions thereof being seen in dotted lines B, C and solid lines D in Figure 5) and is then turned reversely to connected or interlocked position with the first link 1 (seen in Figures 1 and 2), in which position the bight portion 3 of the first link 1 engages both sides 10 of the second link 9. These movements, of course, are reversed in disconnecting or unlocking the links 1 and 9.

It will be seen that these interlocking links are securely held against accidental unlocking. My invention may be applied to various uses; as instance, the cross chains in "anti-skidding" chains used on automobile tires.

I claim:

1. In a device of the character described; a first link having spaced opposite sides, a bight portion connecting the sides, and a tongue carried by the bight portion and extending in planes spaced inwardly from the sides and having a middle portion bowed outwardly from the sides; and a second link having spaced opposite sides parallelly U-shaped, and bight portions connecting the sides, and being adapted to be inserted between the sides of the first link and passed around the point of its tongue and along the tongue to a position in which the bight portion of the first link engages both sides of the second link.

2. In a device of the character described; a first link having spaced opposite sides, a bight portion connecting the sides, and a tongue carried by the bight portion and extending in planes spaced inwardly from the sides, first in the longitudinal direction of the link outwardly from the bight portion,

then in bowed form outwardly from the sides, and then to its point between the sides; and a second link having spaced opposite sides parallelly U-shaped, and bight 5 portions connecting the sides, and being adapted to be inserted between the sides of the first link and passed around the point of

its tongue and along the tongue to a position in which the bight portion of the first link engages both sides of the second link. ¹⁰

In testimony whereof I have hereunto set my hand at Grand Rapids, Michigan, this 25th day of October, 1922.

JULIUS G. BALCERWICZ.
